CLAIM

The ornamental design for pendant lamp, as shown and described.

DESCRIPTION

FIG. 1 is a front perspective view of a pendant lamp showing my new design;

FIG. 2 is a side elevational view thereof on a reduced scale, the opposite side and rear being identical;

FIG. 3 is a top plan view thereof on a reduced scale;

FIG. 4 is a bottom plan view thereof on a reduced scale;

FIG. 5 is a front perspective view of a second embodiment of my new design;

FIG. 6 is a side elevational view thereof on a reduced scale, the rear and opposite side being identical;

FIG. 7 is a top plan view thereof on a reduced scale;

FIG. 8 is a bottom plan view thereof on a reduced scale;

FIG. 9 is a front perspective view of a third embodiment of my new design;

FIG. 10 is a side elevational view thereof on a reduced scale, the rear and opposite side being identical;

FIG. 11 is a top plan view thereof on a reduced scale;

FIG. 12 is a bottom plan view thereof on a reduced scale.

The fixture is shaded to indicate translucency.
